ROTARY BIN

Original Filed April 30, 1921

UNITED STATES PATENT OFFICE.

WILBUR B. HODGES, OF BROWNSVILLE, SOUTH CAROLINA.

ROTARY BIN.

Application filed April 30, 1921, Serial No. 465,766. Renewed July 30, 1923.

To all whom it may concern:

Be it known that I, WILBUR B. HODGES, a citizen of the United States, residing at Brownsville, in the county of Marlboro and 5 State of South Carolina, have invented certain new and useful Improvements in Rotary Bins, of which the following is a specification, reference being had to the accompanying drawings.

10 This invention relates to certain improvements in rotary bins and has relation more particularly to a device of this general character especially designed and adapted for use in connection with groceries and kindred 15 commodities, and it is an object of the invention to provide a novel and improved device of this general character divided into compartments adapted to receive different commodities and whereby such commodities 20 are effectively protected against dust and insects and against moisture.

Furthermore it is an object of the invention to provide a novel and improved device of this general character particularly 25 designed for use in connection with a grocery store, and which is adapted to contain different commodities and in a manner whereby the possibility of mixing said commodities is substantially eliminated.

30 Another object of the invention is to provide a novel and improved device of this general character adapted for use in connection with commodities to be sold in bulk and wherein the same may be positioned in 35 close proximity to a scale so that a sale may be effected with a minimum of effort on the part of the salesman.

An additional object of the invention provides a novel and improved device of this 40 general character embodying a receptacle supported for rotation and wherein said receptacle is permanently divided into a plurality of compartments together with means whereby each of said compartments may be 45 subdivided at will.

It is a further object of the invention to provide a novel and improved device of this general character comprising a receptacle 50 rotatively supported beneath a counter and wherein said counter has a portion above the receptacle cut away to facilitate ingress to the receptacle, together with means whereby the portion of the receptacle adjacent the counter may be maintained closed to occlude 55 the entrance within the receptacle of dust, insects and the like.

The invention consists in the detail of construction and in the combination and arrangement of the several parts of my improved rotary bin whereby certain important advantages are attained and the device rendered simpler, less expensive and otherwise more convenient and advantageous for use, as will hereinafter more fully be set forth.

60 The novel features of my invention will hereinafter be definitely claimed.

In order that my invention may be the better understood, I will now proceed to describe the same with reference to the accompanying drawings, wherein:

Figure 1 is a fragmentary view in top plan illustrating a bin constructed in accordance with an embodiment of my invention with the movable shutter or lid in 75 closed position;

Figure 2 is a sectional view taken substantially on the line 2—2 of Figure 1;

Figure 3 is a view in top plan of the device as herein disclosed with the counter, 80 and the shutter or lid in a partially open position;

Figure 4 is a sectional view taken substantially on the line 4—4 of Figure 2 with a removable partition in applied position.

85 As disclosed in the accompanying drawing C denotes a fragmentary portion of a counter provided in one of its marginal portions, preferably the inner marginal portion thereof, with a cut out portion or recess 1, herein disclosed as semicircular in form, although I do not wish to be understood as limiting myself to this particular configuration.

90 Secured to the underface of the counter C inwardly of, but in relatively close proximity to the central portion of the recess 1, is a bearing 2 in which is engaged the reduced end portion 3 of a vertically disposed shaft 4. The opposite end portion of the 100 shaft 4 is engaged within the bearing 5 secured to the floor F or other surface.

95 Rotating with the shaft 4 is a receptacle R herein disclosed as cylindrical in form, with its upper end open and terminating in 105 relatively close proximity to the counter C. The diameter of the receptacle R is such as to cause the same to underlie the recess 1, but not extending beyond the inner margin of the counter C or that marginal portion of the counter C provided with the opening 1.

The shaft 4 has its lower portion disposed through the axial center of the bottom 6 of the receptacle R, and the portion of the bottom 6 surrounding the shaft 4 is 5 provided with the hub 7 directly above the bearing 5. Interposed between the bearing 5 and the hub 7 are the antifriction members 8, so that the shaft 4 together with the receptacle R may be rotated with a mini- 10 mum of frictional resistance.

Intersecting the space between the shaft 4 and the peripheral wall 8 of the receptacle R are the permanent partitions 9 herein disclosed as four in number, and substantially 15 equidistantly spaced. The partitions 9 divide the receptacle R into a plurality of compartments and each of the compartments may be subdivided upon the application 20 thereof of a removable partition 10. Each of the compartments between the partitions 9 is provided with the guideways 11 to receive a partition 10, one of said guideways extending lengthwise of the shaft 4 and the second guideway being carried by 25 the peripheral wall 8 in radial alignment with the first named guideway.

Disposed over the upper or open end of the receptacle R is a cover A, the reduced portion 3 of the shaft 4 extending through 30 the axial center of said cover A. The cover A is nonrotatable, and as herein disclosed, said cover A is held against rotation by a pin 12 depending from the counter C and extending within an opening 14 in the 35 cover A.

The portion of the cover A underlying the recess 1 in the counter C is cut out, as at 15, to provide an opening whereby ingress may be had to the various compartments 40 of the receptacle R as said receptacle is rotated. The periphery of the cover A between the opposite ends of the cut away portion 15 is defined by a depending flange 16 which overlaps the upper end portion 45 of the receptacle R.

Coacting with the cut away portion or entrance opening 15 of the cover A is a shutter or lid 17 of a size to close the cut away portion or opening 15. The shutter or lid 50 17 as herein disclosed is in the segment of a circle and its apex portion has disposed therethrough the reduced portion 3 of the shaft 4 whereby the shutter or lid 17 is

supported for free swinging movement in opposite directions. The outer or arcuate margin of the shutter or lid 17 is defined by a depending flange 18 overlying the adjacent or upper portion of the receptacle R. Extending upwardly from the shutter or lid 17 is a knob 19 or the like, whereby desired swinging movement may be imparted to the shutter or lid 17. 55 60 65

In practice, each of the compartments of the receptacle R is adapted to contain a desired commodity, preferably in bulk, and in effecting a sale of any one of the particular commodities it is only necessary to rotate the receptacle R until the compartment of the receptacle containing the desired commodity is positioned substantially 70 below the cut out portion or opening 15 in the cover A, whereupon the shutter or lid 17 is swung into open position.

The shutter or lid 17 may be swung into open position, if preferred, before the receptacle R is rotated to gain access within the desired compartment of the container. 75

From the foregoing description it is thought to be obvious that a rotary bin constructed in accordance with my invention 80 is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in 85 carrying out my invention in practice except as hereinafter claimed. 90

I claim:

In combination with a counter provided with a recess in a marginal portion thereof, a rotary receptacle positioned below the counter and extending below the recess of the counter, the upper face of the receptacle being open, a nonrotatable cover coacting with the open end of the receptacle, said cover being provided with an opening to permit access within the receptacle and means for closing said opening. 95 100

In testimony whereof I hereunto affix my signature.

WILBUR B. HODGES.
